Primary Examiner — Abraham Bahta

CLAIM

The ornamental design for a display with font, as shown and described.

DESCRIPTION

FIG. 1 is a front, bottom, and left side perspective view of our new design for a display with font;
FIG. 2 is a front, top, and left side perspective view thereof;
FIG. 3 is a front side view thereof;
FIG. 4 is a back side view thereof;
FIG. 5 is a top side view thereof;
FIG. 6 is a bottom side view thereof;
FIG. 7 is a left side view thereof; and,
FIG. 8 is a right side view thereof.

The broken lines showing environment in the drawings are for illustrative purposes only and form no part of the claimed design.

1 Claim, 2 Drawing Sheets
